UNITED STATES PATENT OFFICE.

WILLIAM H. BUSHNELL AND WILLIAM H. VAN GILDER, OF PERRYSVILLE, OHIO.

SIGN-BOARD.

SPECIFICATION forming part of Letters Patent No. 325,817, dated September 8, 1885.

Application filed April 18, 1884. (No model.)

To all whom it may concern:

Be it known that we, WILLIAM H. BUSHNELL and WILLIAM H. VAN GILDER, of Perrysville, county of Ashland, and State of Ohio, 5 have invented certain new and useful Improvements in Sign-Boards, of which the following is a full, clear, and exact description.

The object of our invention is to provide a new and improved sign-board on which metal 10 or other raised letters are to be fastened, which sign-board is so constructed that the letters are protected to a great extent from snow, rain, &c., and which sign-board is also so constructed that water cannot leak between the 15 board and its metal covering.

The invention consists in a sign-board having all its surfaces covered with sheet metal.

The invention further consists in a sign-board covered with sheet metal, and having 20 a flange or guard projecting from the front and back surfaces at the top.

The invention also consists in the combination, with a board covered with sheet metal, of malleable-iron letters held on the said sign-board.

Reference is to be had to the accompanying drawings, forming a part of this specification, in which similar letters of reference indicate corresponding parts in all the figures.

30 Figure 1 is a perspective view of our improved sign-board, parts being broken out and others shown in section. Fig. 2 is a cross-sectional elevation of the same. Fig. 3 is a longitudinal sectional elevation of one end of 35 the same on the line $x-x$, Fig. 2. Fig. 4 is a perspective view of a modification of the sign-board. Fig. 5 is a cross-sectional elevation of the same. Fig. 6 is a cross-sectional elevation of another modification. Fig. 7 is a 40 plan view of the sheet-metal plate for covering the sign-board shown in Fig. 4. Figs. 8 and 9 are cross-sectional elevations of two 45 modifications of the sign-board. Fig. 10 is a longitudinal sectional elevation of one end of the sign-board shown in Fig. 9, on the line $y-y$ of the same.

The board A, Figs. 1, 2, and 3, is covered on its front, back, and top and bottom edges by a piece of sheet metal, B, which has its longitudinal edges joined at a —that is, at the bot-

tom of the rear surface of the board. The sheet metal is doubled over at the top of the front of the board to form an outwardly-projecting flange or guard of double thickness at the top of the front of the sign-board. 55

The sheet metal B is nailed to the board A at the bottom only, and no nails, screws, &c., are passed through the sheet metal into the top of the board or at the top and sides, thus making it impossible for water to leak in at 60 the top or sides of the sign-board.

The sheet-metal end pieces, D, are bent at the top and bottom ends over the top and bottom edges of the board A, and are then nailed down, the said bent ends and the nails being 65 covered by the sheet metal B.

The letters, made of malleable iron, are screwed on the front of the sign-board below the flange or guard C. In the construction shown in Figs. 4, 5, 6, and 8 the front, back, 70 top, bottom, and ends of the board are covered by a single piece, B', of sheet metal, (shown in Fig. 7,) the wings b covering the ends of the board.

A top plate, D, covered with sheet metal, is 75 secured by screws on the top of the sign-board in such a manner that the said plate projects from the front of the sign-board and forms a guard, as shown in Fig. 5. The inner edge of the sheet metal on the under side of the top 80 plate abuts against the front of the sign-board.

If desired, a plain uncovered top plate, E, can be secured on the top edge of the sign-board to form the flange or guard.

In place of the wooden top plate, covered or 85 uncovered, a metal top plate, F, can be provided, which projects from the front and rear surfaces of the sign-board. This top plate can consist of a piece of sheet metal doubled over, as shown in Fig. 8, which top plate is 90 held on the sign-board by screws, or a top plate, H', can be formed by doubling over the sheet metal covering the board in the same manner as the flange is formed on the sign-board. (Shown in Figs. 1 and 2.) 95

The above-described sign-boards are very simple in construction, strong and durable, can be made any size, and covered with sheet-iron, plain or galvanized, sheet-copper, zinc, &c.

Having thus described our invention, we claim as new and desire to secure by Letters Patent—

1. A sign-board having all its surfaces covered with sheet metal, substantially as herein shown and described.
2. A sign-board having its front, rear, top, and bottom surfaces covered by a single piece of sheet metal secured to the board at the bottom edge of the same, substantially as herein shown and described.
3. A sign-board having its front, rear, top, bottom, and end surfaces covered by a single continuous piece of sheet metal, substantially as herein shown and described.
4. A sign-board having all its surfaces covered with metal and provided with a guard at its top, substantially as herein shown and described.
5. A sign-board covered with metal and having a flange or guard projecting from the front and from the rear surfaces at the top edges of the same, substantially as herein shown and described.

6. The combination, with a sign-board, of 25 the metal end pieces, D, nailed to the top and bottom edges of the board, and the sheet-metal covering B, forming a projecting flange or guard, C, and nailed or fastened to the board at the bottom, substantially as shown and de- 30 scribed.

7. The combination, with a sign-board covered with metal, of malleable-iron letters secured on the covering and board, substantially as herein shown and described.

8. As a new article of manufacture, a sign-board having all its surfaces covered with metal and provided with a guard at its top, and with malleable-iron letters on said metal covering, as set forth. 35
